(57) **CLAIM**

The ornamental design for a modular cartridge assembly, substantially as shown and described.

DESCRIPTION

FIG. 1 is a perspective view of a modular cartridge assembly embodying the invention showing interlockable inlet module assembly, cartridge body assembly, and reagent tray components.

FIG. 2 is a front view of the modular cartridge assembly.

FIG. 3 is a rear view of the modular cartridge assembly.

FIG. 4 is a left side view of the modular cartridge assembly.

FIG. 5 is a right side view of the modular cartridge assembly. FIG. 6 is a bottom view of the modular cartridge assembly; and,

FIG. 7 is a top view of the modular cartridge assembly. The vacutainer tube and tubes shown in broken lines FIGS. 1-5 and 7 represent the environmental subject matter. The broken lines immediately adjacent the claimed areas in FIGS. 1, 6 and 7 represent the bounds of the claim. None of the broken lines form a part of the claimed design.
